UNITED STATES PATENT OFFICE.

WILLIAM H. H. PITTMAN, OF STILLWATER, OKLAHOMA TERRITORY.

TRUSSSED SUSPENSION-BRIDGE.

SPECIFICATION forming part of Letters Patent No. 634,026, dated October 3, 1899.

Application filed May 29, 1899. Serial No. 718,732. (No model.)

To all whom it may concern:

Be it known that I, WILLIAM H. H. PITTMAN, a citizen of the United States, residing at Stillwater, in the county of Payne and Territory of Oklahoma, have invented a new and useful Trussed Suspension-Bridge, of which the following is a specification.

My invention relates to improvements in trussed suspension-bridges designed to make the parts strain each other mutually, so as to attain the desired camber on the longitudinal stringers and to increase the resistance of the parts to strain in proportion to the load imposed upon the structure; and the object in view is to provide a simple structure adapted to be easily and readily erected across a stream or chasm.

With these ends in view the invention consists in the novel combination and construction of parts, which will be hereinafter fully described and claimed.

In the drawings, Figure 1 is a plan view of my suspension-bridge with the flooring omitted. Fig. 2 is a longitudinal sectional elevation through the bridge shown by Fig. 1 and representing the flooring applied to the stringers. Fig. 3 is a vertical transverse section on the line 3 3 of Fig. 1, showing one method of bracing the inclined depending struts. Fig. 4 is a similar transverse section on the line 4 4 of Fig. 1, illustrating another construction of braces for the struts. Fig. 5 is an enlarged detail section on the line 5 5 of Fig. 2, showing the means by which each deflected cable is confined in position on one of the struts.

The same numerals of reference are used to denote like and corresponding parts in each of the several figures of the drawings.

In carrying my invention into practice I employ a pair of head-beams 10 11, which are seated upon the piers or abutments 12, the latter being erected on opposite sides of the stream or chasm across which it is desired to erect the improved suspension-bridge. In connection with the head-beams 10 11 I employ a series of longitudinal stringers 13, which are seated in recesses 14, provided in the opposing edges of the head-beams 10 11. Said beams are arranged in horizontal positions on the piers or abutments, so as to lie parallel one with the other, and said beams

are confined in place by being buried in the embankments or by any other suitable means. The seats 14 are produced in the opposing edges of the head-beams, and the series of seats in each beam are spaced correspondingly to the intervals between the series of stringers. As shown by Figs. 1, 3, and 4, a series of four stringers are employed to extend continuously from one head-beam to the other, and these stringers are fitted in the recesses of the head-beams so as to be exposed to endwise pressure from the solid faces on the head-beams, whereby the stringers are kept in the arched condition represented by Fig. 2 in order to produce the desired camber in the structure.

Below the series of arched longitudinal stringers are arranged the transverse beams 15, which are spaced at suitable intervals one from the other and which lie parallel to the head-beams and to each other. These cross-beams engage directly with the lower faces of the series of longitudinal stringers, and from the ends of the cross-beams depend the struts 16, which are inclined outwardly, as shown by Figs. 3 and 4. A pair of these depending inclined struts are provided on each cross-beam 15 near the ends thereof, and the struts on the middle cross-beam are somewhat longer than the struts on either of the cross-beams which lie on opposite sides of the middle cross-beam. (See Fig. 2.)

In order to strain the head-beams 10 11 to produce the endwise pressure of the longitudinal stringers, I employ the cables 17 18, which are connected operatively with the head-beams and are engaged with the lower ends of the series of struts that depend from the cross-beams. These cables are disposed at opposite sides of the bridge to extend the full length thereof, and each end of each cable is looped around one end of one head-beam, said loops being indicated by the numeral 19. The free end of the bight or loop of the cable is confined in place by means of the clip 20 of any suitable construction. (See Fig. 2.) To prevent the cable from being displaced relatively to the inclined struts, a series of yokes 21 are fastened to the lower ends of the struts in positions to embrace the cables. Said lower ends of the struts are provided with recesses 22, adapted to receive the cables,

as shown by Figs. 3 and 4 and more clearly represented by Fig. 5. Each yoke is fitted to one of the struts to embrace opposite side faces thereof and to confine the cable in the recess 22, and said yoke is fastened to the strut by the transverse bolt 23, which passes through the strut and the arms of the yoke. (See Fig. 5.)

To brace the joint between each cross-beam and its depending struts, I employ braces, as shown by Figs. 3 and 4. The short struts on the intermediate cross-beams are stayed by the diagonal braces 24, shown by Fig. 4 as fitting in the space between the struts and the cross-beam; but with the long struts on the middle cross-beam I employ the tie-bar 25, as shown by Fig. 3. These struts are fastened in any suitable way to the cross-beams, and the braces 24 or 25 are secured either to the struts and cross-beam or to the struts themselves.

To further stay the struts and strengthen the bridge structure in its entirety, I employ the side truss-rod 26, which are arranged to cross each other and are fastened at 27 28 to the upper and lower parts of the series of struts on each side of the bridge, thus staying the struts against collapsing lengthwise of the bridge.

The stringers are stayed by the crossed truss-rod 29, which extend diagonally from opposite ends of the cross-beams 15 and in the intervals between the same, and these horizontal truss-rod are fastened at 30 31 through opposite ends of the cross-beams in any suitable way.

The floor 32 is laid across the series of arched stringers. This floor may consist of suitable planks laid crosswise upon and firmly secured to the stringers; but the material of the floor and the method of fastening the same in place may be varied within wide limits.

The bridge is equipped with hand-rails 33 on each side thereof, and said rails are fastened to the posts 34, which are secured to the cross-beams 15. The posts also support the guard-rails 35, and said posts are stayed by the braces 36.

From the foregoing description it will be noted that the side cables 17 18 are curved or inclined in an opposite direction to the camber of the stringers and the floor and that the cables tend to exert strain on the head-beams 10 11, so as to draw them toward each other in a direction to impose endwise pressure upon the stringers, the latter being confined against distortion or displacement by fitting the ends thereof in the seats of the head-beams. This arrangement and connection of the several elements composing the improved suspension-bridge strains the several parts to insure uniformity in the distribution of the load imposed upon the bridge-floor, and another important advantage which is secured by the improved structure resides in the fact that the resistance of the stringers is increased

in proportion to the load imposed upon the bridge. The side cables which strain the head-beams are confined in proper relation to the stringers by engagement with the struts, and displacement of the cables with relation to the struts is wholly overcome by the yokes which are fastened individually to the struts.

The several parts are of simple and durable construction, so that the bridge may be readily assembled and erected.

The parts may be made of either wood or metal, or a combination of these materials may be adopted in the construction of the bridge; but it is preferable to make the cables of wire strands which are twisted or intertwined together.

As shown by Fig. 5, the lower recessed end of the strut may receive a metallic saddle 22^a, 85 against which the cable may bear, and this saddle is particularly serviceable when the strut is made of wood, because it prevents the cable from cutting into the wood.

Of course I will avail myself of the services of a skilled constructor in the selection of materials and in the number and arrangement of the parts. Thus the stringers may be seated on piling or any other suitable material in lieu of the piers or abutments, and the number of the stringers may be varied according to the width of the bridge; also, in wide bridges the number of cables may be increased. The braces for the struts and for the stringers or floor may be of cables, each composed of wire strands laid straight and wrapped or twisted as desired; but, if desired, the braces for said parts may be of metallic rods or even wood braces under certain conditions, the materials used being varied within the skill of the constructor.

Changes may be made in the form and proportion of some of the parts while their essential features are retained and the spirit of the invention embodied. Hence I do not desire to be limited to the precise form of all the parts as shown, reserving the right to vary therefrom.

Having thus described the invention, what I claim is—

1. A trussed suspension-bridge consisting of the head-beams, arched stringers seated on said head-beams and subjected to endwise pressure thereby, cross-beams engaging with the stringers and provided with depending struts, and cables engaging with said struts and with the head-beams, substantially as described.

2. A trussed suspension-bridge comprising the head-beams, the stringers seated thereon, cross-beams engaging with said stringers, the struts depending from the cross-beams and provided with recesses in their lower edges, cables attached to the head-beams and fitted in the recesses of the struts, and yokes secured to the struts and engaging with said cables to confine the latter in the recesses of the struts, substantially as described.

3. In a trussed suspension-bridge, the de-

pending struts provided with recesses in their lower edges, a cable fitted in said recesses, and yokes bolted to the struts and extending across the lower recessed edges thereof to confine the cable in said recesses, substantially as described.

4. A trussed suspension-bridge comprising the head-beams having recesses or seats, the arched stringers fitted in said recesses, the cross-beams, the struts united and stayed to said cross-beams, the side cables fastened to the head-beams and engaging with the lower ends of the struts, means for confining the

cables against displacement with relation to the struts, the truss-rods arranged at the sides of the bridge and engaging with the struts thereof, and the diagonal truss-rods united to the cross-beams, substantially as described. 15

In testimony that I claim the foregoing as my own I have hereto affixed my signature in 20 the presence of two witnesses.

WILLIAM H. H. PITTMAN.
